(57) **CLAIM**

The ornamental design for an electric scooter, as shown and described.

DESCRIPTION

1. Electric scooter

1.1: Front, right-side, top perspective in a folded state

1.2: Front, left-side, top perspective in an un-folded state

1.3: Front elevation in the unfolded state

1.4: Left-side elevation in the folded state

1.5: Right-side elevation in the unfolded state

1.6: Bottom plan in the folded state

1.7: Top plan in the unfolded-state.

The broken lines depict portions of the electric scooter that form no part of the claimed design.
